(57) **CLAIM**

The ornamental design for padding for goggles, as shown and described.

DESCRIPTION

This application relates to the co-pending design U.S. Ser. No. 29/881,264, filed Dec. 29, 2022, herein incorporated by reference.

FIG. 1 is a front elevation view of padding for goggles showing my new design.

FIG. 2 is a rear elevation view thereof.

FIG. 3 is a right side elevation view thereof, the left side being a mirror image thereof.

FIG. 4 is a top plan view thereof.

FIG. 5 is a bottom plan view thereof.

FIG. 6 is a top, front, left perspective view thereof.

FIG. 7 is a bottom, left, front perspective view thereof.

FIG. 8 is a top, right, rear perspective view thereof; and,

FIG. 9 is a bottom, right, rear perspective view thereof.

Elements drawn in broken lines represent environmental features, such as a frame for the goggles, that form no part of the claimed design.

1 Claim, 9 Drawing Sheets
